UNITED STATES PATENT OFFICE.

GEORGE A. E. JONES, OF NEW LONDON, CONNECTICUT, ASSIGNOR TO UNITED STATES ELECTRIC COMPANY, A CORPORATION OF CONNECTICUT.

ELECTRIC RIVET-HEATING APPLIANCE.

1,313,538.

Specification of Letters Patent.

Patented Aug. 19, 1919.

Application filed April 25, 1919. Serial No. 292,542.

To all whom it may concern:

Be it known that I, GEORGE A. E. JONES, a citizen of the United States, and resident of New London and county of New London and State of Connecticut, have invented an improvement in Electric Rivet-Heating Appliances, of which the following description, in connection with the accompanying drawings, is a specification, like reference characters on the drawings representing like parts.

This invention relates to an electric heating appliance or tool and is intended as an improvement on the portable electrode or tool for heating rivets forming the subject of my patent numbered 1,297,570, dated March 18, 1919 for apparatus for hot riveting.

The present improvement is embodied in the tool or electrode which is to be applied by the operator to the end of the rivet to be heated and thereafter to be headed or upset against the plating or material to be united by the rivet.

The invention consists in part in an electrode composed of two conducting portions of which the one which is to make contact with the material to be heated is yieldingly movable relative to the other, or main body portion, and there being a normally open circuit closer between the two parts which is closed by the yielding movement of the contacting portion when pressed with sufficient force against the rivet to be heated.

The invention further consists in certain features of construction which will be hereinafter described in connection with the accompanying drawings in which:

Figure 1, is a longitudinal section partly in elevation of an electrode or heating tool embodying this invention.

Fig. 2, a side elevation thereof on a smaller scale, also illustrating the rivet to be heated and the companion electrode applied to the head of the rivet, and

Fig. 3, a side elevation partly in section of a removable tip forming a part of the contacting portion of the electrode or heating tool.

Referring to Fig. 1, the electrode forming the subject of this invention comprises a main body portion 2, which may be made of copper, and a movable contacting portion 3; these parts being inclosed in the covering of insulating material 4 which is itself

inclosed in a protecting shield 5 substantially as in the construction shown in my former application, except for certain structural features which will be hereinafter described.

Interposed between the main body portion 2 and the movable contacting portion 3 of the electrode is a circuit closing device composed of a contacting spring 12, secured to, but insulated from, the main body portion 2 of the electrode as shown, and having its free end in contact with the inner surface of the movable contacting portion 3 of the electrode in proper relation to an anvil 13 secured to or forming a part of the main body portion 2 of the electrode and being in electrical continuity therewith.

The movable contact 12 of the circuit-closer is made as, or is provided with, a spring which acts to force the contacting portion 3 of the electrode outward or away from the main body portion 2, and when free to act holds the said portion 3 in its outermost position and is itself separated from the anvil 13 so that the current which is supplied to the main body portion 2 by the flexible conductor or cable 20 does not pass to the contacting portion 3 of the electrode.

The said contacting portion 3 has its outer or exposed part of somewhat smaller diameter than the part that is fully contained in the insulating material 4, thus forming a shoulder 30 which in conjunction with the annulus 40 forming a part of the insulating covering of the electrode, serves as a stop to limit the outward movement of the contacting portion 3 of the electrode, which thus normally stands electrically separated from the main portion 2 as shown in Fig. 1.

The protecting shield 5 which may be made of iron or other durable material is made in this instance in the form of a cylindrical shell having at one end the inwardly turned flange 52 which covers the end of the insulated electrode, except for the opening through which the cable 20 or its terminal plug 22 enters to make connection with the main body 2 of the electrode.

At the other end the covering shield 5 is screw threaded and a correspondingly threaded flanged ring 53 is screwed thereon into engagement with the annulus 40 of insulating material and thus retains the movable contacting portion 3 in proper operative relation to the main portion 2 of the electrode and protects the insulated electrode.

from damage in the handling to which it is subjected when in use.

As shown in Fig. 2 the shield of the insulated electrode may be provided with a suitable handle 55 to facilitate its manipulation by the operator, who presses the contacting portion against the end of the rivet to be heated as illustrated in Fig. 2, in which the rivet to be headed is marked 60, the plates or structural parts to be united thereby are marked 61 and 62 and the companion electrode or heating tool applied to the head of the rivet is marked 63.

I have discovered that a more uniform and effective heating is obtained when the electrode makes contact with the rivet around the periphery or circumferential edge, thereof, and in order to effect such heating the contacting end of the contacting portion 3 of the electrode is made with a recess 32, having a conical or tapering surface 33.

Thus when the electrode is pressed against the end of the rivet as illustrated in Fig. 2 the circumferential edge of the rivet will make contact with the tapering or conical wall 33 of the recess 32, and the same effect will be produced with rivets of different size, as a smaller rivet will come to its bearing at a greater depth in the recess than a larger rivet.

If however as shown in Fig. 1, the recess in the end of the contacting part was sufficiently large to coöperate with the largest sized rivets commonly used, and said recess is also made deep enough for quite small rivets, the extreme end of the electrode would be likely to come in contact with the plate in which the rivet is to be heated, before coming into full contact with the tip of the rivet.

In order to provide for rivets of the range of sizes commonly used, the tip portion 34 of the contacting portion 3 of the electrode is made removable, and an additional tip such as is illustrated in Fig. 3 is provided having a recess 32 with a tapering wall 33 such as already described but of smaller size than that shown in Fig. 1.

In order to provide for removing the tip 34, it is provided with a threaded shank 35 which screws into a corresponding recess in the inner portion of the contacting part 3 and said removable tip is shown as provided with wrench faces 36 to facilitate the operation of applying it to or removing it from the other part that remains contained in the insulated shield, and said part is provided with a recess 37 to be engaged by a holding-pin which may be inserted through a hole 38 in the shield and insulation in order to prevent the inner part of

the contacting portion 3, from turning when the removable tip is being screwed on to the same or unscrewed therefrom.

The two tips with recesses of the relative size indicated will be sufficient for all of the sizes of rivets that are commonly used in the work in which the heating tool is employed.

As it is sometimes desirable to detach the electrode from the conducting cable 20, the latter is shown as provided with a connecting plug 22, having a recess or bore 23 in which the end of the cable is secured and preferably soldered to insure the electrical conductivity, said plug being detachably fastened in the end of the main body portion 2 of the electrode in any suitable way as by the bayonet joint construction illustrated in Fig. 1, in which pins 24 secured in the body 2 of the electrode project into the plug socket and engage with the plug in grooves 25 thereof as will be readily understood.

What I claim is:—

1. A freely movable implement for heating rivets comprising an electrode composed of a main body portion, and a yieldingly movable contacting portion having a contact surface to be placed in contact with the exposed end of the rivet to be heated, and a normally open circuit closer between said portions adapted to be closed by the yielding movement of the contacting portion when the main body of the electrode is forcibly pressed toward the rivet substantially as described.

2. In a freely movable implement for heating rivets an electrode having a contacting portion to be placed in contact with the exposed end of the rivet to be heated, said contacting portion having a tapering recess in its rivet engaging end whereby contact is made with the rivet around the periphery thereof, substantially as described.

3. In an implement for heating rivets a freely movable electrode comprising a body portion and a yieldingly movable contacting portion, and a normally open circuit closer interposed between said portions, combined with an insulating covering for said electrode and a protecting shield inclosing said covering, said insulating covering and shield supporting the movable contacting portion of the electrode in proper relation to the main portion and limiting the outward movement of said contacting portion substantially as described.

In testimony whereof, I have signed my name to this specification.

GEORGE A. E. JONES.
